DESIGN FOR A FLOWER CONTAINER

Roderick I. McLellan, San Francisco, and Wilson J. Field, Orinda, Calif., assignors to E. W. McLellan Co., San Francisco, Calif., a copartnership

Application May 19, 1945, Serial No. 119,620

Term of patent 14 years

(Cl. D58—12)

To all whom it may concern:

Be it known that we, Roderick I. McLellan and Wilson J. Field, citizens of the United States of America, residing at the city and county of San Francisco and State of California, and Orinda, county of Alameda and State of California, respectively, have invented a new, original, and ornamental Design for a Flower Container, of which the following is a specification, reference being had to the accompanying drawing forming part thereof.

Fig. 1 is a plan view of a flower container, showing our new design.

Fig. 2 is a side view of the container of Fig. 1. Fig. 3 is an end view of the container of Fig. 1.

Opposite sides and opposite ends of the container are the same as shown in Figs. 2, 3, respectively, and the bottom is plain.

We claim:

The ornamental design for a flower container, as shown and described.
